MACHINE FOR DRIVING CURVED SELF-RETROVERTING NAILS

John N. M. Howells, Kittery, Maine

Application April 19, 1943, Serial No. 483,594

24 Claims. (Cl. 1—46)

1

This invention relates to a machine for driving curved self-retroverting nails, the same being of the type disclosed in my co-pending application for Fastening devices and means for applying the same, Serial No. 440,342, filed April 24, 1942. In said application I have shown a tool for driving a curved, self-retroverting nail by successively applying to portions of the nail shank, as they pass beneath the point of application, a force substantially normal to the surface of the material into which the nail is being driven. While such tool is quite simple in construction, it is particularly adaptable for manual operation, and, due to the many blows required by it to drive a nail home, does not lend itself to use in a high speed, self-powered device for driving nails of the character described.

It is, therefore, an object of my invention to provide a machine which can drive home a nail of the character described with one blow or at the most two blows, the latter only being required when the nail extends arcuately close to 180°.

Another object of my invention is to provide a machine which can drive home a nail of the character described with one or more blows normal to the head and thus not applied normal to the surface of the material into which the nail is being driven.

In my aforesaid co-pending application the self-clinching nail has been illustrated as having a plurality of notches in the shank. While this simplified the construction of the driving tool, it somewhat weakened the nail and the shank had to be of a slightly greater diameter in the notched portions than would normally be required under given conditions. It is, therefore, a further object of the present invention to provide a machine or tool for driving a nail of the character described having a shank of uniform cross-section.

An additional object of my invention is to provide a self-powered machine for driving nails of the character described, which shall comprise relatively few and simple parts, and be rugged in construction, efficient, quick and durable in operation, and economical to manufacture and use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the appended claims.

2

In the accompanying drawings, in which is shown one of the various possible embodiments of this invention,

5 Fig. 1 is a side view of a curved self-retroverting nail adapted to be driven by a machine embodying my invention;

Fig. 2 is a top plan view of said nail;

Fig. 3 is a sectional view of the nail shank taken substantially along the line 3—3 of Fig. 1;

10 Fig. 4 is an auxiliary plan view of the nail head taken substantially along the line 4—4 of Fig. 1;

Fig. 5 is a top plan view of a nail driving machine embodying the invention with the nail magazine partly broken away;

15 Fig. 6 is a central longitudinal section taken substantially along the line 6—6 of Fig. 5 and illustrating the various means for applying and controlling the application of power to the means for actuating nail driving elements;

20 Fig. 7 is a central longitudinal section through the means for actuating the nail driving elements and through the nail holding magazine;

25 Figs. 8 and 9 are enlarged sections taken substantially along the lines 8—8 and 9—9 of Fig. 7 and illustrating the gear trains forming part of the means for actuating the first acting and second acting nail driving elements respectively;

30 Fig. 10 is an enlarged sectional view taken substantially along the line 10—10 of Fig. 7 and illustrating the first acting nail driving element and the means for actuating the same immediately prior to the initiation of an operative stroke;

35 Fig. 11 is a sectional view taken substantially along the line 11—11 of Fig. 10 and showing a detail of the means for actuating the first acting nail driving element;

40 Fig. 12 is a sectional view taken substantially along the line 12—12 of Fig. 7 and illustrating the means for actuating the second acting nail driving element while the same is at rest;

45 Fig. 13 is a sectional view taken along the line 13—13 of Fig. 12 and showing a detail of the means for actuating the second acting nail driving element;

Fig. 14 is a view similar to Fig. 10 with the parts positioned at the end of an operative stroke of the first acting nail driving element;

50 Fig. 15 is a sectional view taken substantially along the line 15—15 of Fig. 14;

Fig. 16 is a sectional view taken substantially along the line 16—16 of Fig. 7 after the completion of the stroke of the second acting nail driving element; and

55 Fig. 17 is a sectional view taken substantially

along the line 17—17 of Fig. 7 and illustrating details of the nail holding magazine and the means for feeding nails into driving position.

Referring now to the drawings and more particularly to Figs. 1-4, I have there shown a self-retroverting nail 10 of the same general characteristics and attributes as that illustrated, described and claimed in my said co-pending application. The nail 10 includes a curved shank 12 which is tipped at one end by a driving point 14 and provided at the other end with a head 16.

The shank 12 is preformed to a shape such that the direction of the driving point 14 has a component directly opposed to the direction of travel of the nail head 16. As will later be apparent from the description of the machine for driving the nail, the most easily driven form of shank which has this relative disposition of point and head is a substantially circular segment. Such segment may embrace an arc of from about 90° to about 180°. Obviously the greater the arc the greater will be the self-retroverting effect which is obtained and the greater will be the difficulty in driving the nail. It will later be seen that nails having shanks of an arc greater than 90° but substantially less than 180° can be driven in a machine embodying my invention with but one blow, and that nails embracing an arc of only slightly less than 180° require two blows. However, the provision of a machine for driving both such classes of self-retroverting nails is within the scope of the instant invention.

The cross-sectional contour of the shank 12 may be circular, as illustrated in Fig. 3, or may assume any other desirable or conventional outline, as for example, oval, rectangular or triangular. Also, the nail may be of uniform cross-sectional contour as shown in Figs. 1 and 2, or gradually tapered from head to tip with an abrupt taper at the tip to form a point, or it may be notched as illustrated in my said co-pending application, or barbed or roughened as is common in the art, without affecting the basic construction or operation of my novel machine for driving the same.

The head of the nail may be longer than the diameter of the shank in one dimension, preferably though not necessarily the plane in which the nail is curved, and no greater than said diameter at right angles to this plane. Alternatively, the head may simply comprise an end of the shank and have no portion projecting laterally beyond the same.

To drive the nail into material, the nail point should be applied to the surface of the material at right angles thereto. First the point and next the nail shank are then forced in. During insertion of the shank, the portion entering the material is usually disposed about normally to the surface of the material. As disclosed in my said co-pending application, the nail can be driven in this manner by employing a tool which enables striking successive portions of the nail shank immediately prior to their entry into the surface of the material. However, many blows are required to drive a nail home with such a tool and, in accordance with the present invention, I reduce the number of blows by providing an apparatus, machine or tool in which a driving force is applied to the nail head rather than to the nail shank, which force changes its absolute direction of application as the nail is driven so that said force is always directed substantially perpendicularly to the nail head or tangentially to the head end of the nail shank.

In general, such machine comprises a means for applying a driving force such as described, i. e., a force of variable direction whose path of travel traces the locus of the nail head, and a means for supporting the nail during driving so that the driving force is transmitted along the nail shank to the point thereof, and is not allowed to distort the nail or move the same in any other than the desired manner and direction.

In addition to the foregoing means, the machine may include a means such as a magazine to house and feed a supply of curved nails, self-contained power means to actuate the nail driving means, a frame and housing to unite the various parts of the mechanism or tool into a unitary whole, and a simple manually actuated control means for setting the machine into operation.

Referring now to Figs. 5-17, I have there disclosed a machine 18 which embodies my invention. Said machine may include a thick base 20 which serves as a bed on which the several elements of the machine are mounted, and a lighter casing 22 which cooperates with the bed 20 to form an enclosing housing for the apparatus. The casing and bed are provided with a lifting yoke 23 to facilitate carrying and positioning of the machine. The outline of the bed 20 and casing 22 is generally such as to conform relatively closely to the overall exterior contour of the several elements contained in the housing and which will not be described.

The source of power for the machine is derived from a high speed electric motor 24 (Fig. 6) which is bolted to the bed 20 and is supplied with current by lead wires 25 adapted to be detachably connected to any convenient electric power outlet. The motor shaft 26 is coupled to a fly-wheel 28 through a slip-drive 30 of standard construction, such as a pair of hardened steel discs 30a, 30b, one of which discs 30b is slidably mounted axially of a shaft 30c and pressed by a spring 30d into frictional surface contact with the other disc 30a. Bearing pedestals 32, 34 to either side 45 of the fly-wheel support the fly-wheel shaft 36. Said shaft is coupled to the input shaft of a gear reduction drive 38 whose output shaft turns a one-revolution clutch 40 of conventional design, comprising for example a pair of coaxial members 40a, 40b provided with conical nestable clutch portions which are spaced apart when the clutch is disengaged. The driven clutch member 40b, which is spline connected to the shaft on which it is supported, is urged into engagement with the driving member 40a upon depression of a button 42. Said button is mounted on a shaft 43 vertically reciprocable in the casing 22 and is biased upwardly by a spring 44. At the lower end of the shaft 43 there is attached a cam 45 which is disposed adjacent a rim of the driven clutch member 40b and is adapted to urge said member into engagement with the driving member 40a when the button is pushed. The driven member 40b carries a longitudinally disposed leaf spring 40c in which an inwardly extending rearwardly tapered rib 40d is formed. Said rib is adapted to lie in an annular groove 40e in the driving member 40a when the two members are engaged and serves to keep the clutch in engagement. The spring 40c extends for a substantial distance beyond the rib 40d. This extending portion is adapted to cooperate with a wedge-shaped stopping dog 40f which is shiftable parallel to the axis of the shaft on which the member 40a is supported. The dog 40f is interconnected by a

linkage system (not shown) such that said dog assumes the full line position shown in Fig. 6 when the button 42 is in its upper position, and the dot-and-dash line position when the button 42 is depressed. When it is desired to render the clutch 40 effective, the button 42 is depressed thereby urging the member 40b into engagement with the member 40a and moving the dog 40f to ineffective position. The driven member 40b will then start to revolve, the two clutch members 40a, 40b being held together by the spring 40c. When the button 42 is released, the dog 40f will spring back to stopping (full line) position so that after the member 40b has made one revolution, the spring 40c will engage the dog and ride partially up its inclined surface. This will raise the rib 40d and allow a spring 40g to separate the two clutch members. Frictional engagement between the spring and dog prevents movement of the driven member 40b until the button 42 is again depressed.

The one-revolution clutch 40 turns a shaft 46 on which are mounted two adjacently disposed mutilated gears 48, 50 (Figs. 7, 8, and 9). One of these gears meshes with a cogwheel 52 on a drive shaft 54 journalled in a bearing post 56. The other mutilated gear 50 engages a second cogwheel 58 disposed coaxially of the cogwheel 52 and supported on a sleeve 60 journalled on said drive shaft 54. The cogwheels 52, 58 are keyed to the drive shaft and sleeve respectively. The forward end of the drive shaft 54 is journalled in a standard 62.

A slotted driving crank 64 (Figs. 7 and 10) is secured to the drive shaft immediately adjacent said standard. The slot in said crank may be offset from said drive shaft 54 and has slidably received therein a roller 66 which is journalled on a post 68 projecting from a circularly segmental block 70 (Figs. 10 and 11) which slides in an arcuate channel 72 formed in the wall of the casing 22 adjacent the nail magazine. This channel has a center of curvature substantially coincident with the center of curvature of nails 10 in the nail magazine M. As will be seen in Fig. 11, the mouth 74 of the channel is narrower than the base thereof and the block 70 provided with a shoe 77 which is slidably retained within the channel. To facilitate insertion of the shoe into said channel a portion 76 (Fig. 12) of the channel is cut away so that the mouth thereof is of the full width of the channel base. As will soon be seen, this portion is beyond the normal travel of said block. A portion of the block 70, which projects through the channel mouth, carries a hammer element 78 hereinafter referred to as the "first hammer."

This element is adapted to ride in a semi-circular driving slot 80 in the standard 62. The two ends of the slot are located adjacent the base 20 of the machine (as shown in Fig. 10), the slot being adapted to receive the shank 12 of a nail 10 with the head thereof disposed near one end of the slot and the tip thereof disposed at the other end of the slot. The base is apertured at 81 to permit a reinforcing extension on the back of the first hammer to lie flush with the base of the machine in the starting position of said first hammer. Another aperture 82 is provided in registration with the other end of the slot to allow the nail 10 to pass freely therethrough when said nail is driven. The forward face of the hammer in starting position lies immediately in back of the head of the nail to be driven. One leg 16a (Fig. 10) of the nail head 16 sweeps along the

bottom of the driving slot 80 while the nail is being driven.

When the hammer 78 is in starting position the mutilated gear 48 is so angularly disposed relative to the cogwheel 52 that the mutilated portion has just terminated its travel thereover and the gear is ready to start driving the cogwheel. The unmutilated portion of the gear covers an arc such that upon rotation of the shaft 46 therethrough the cogwheel 52 will turn the drive shaft 54 an angular distance sufficient to move the first hammer through a driving stroke of substantial angular length, which in the illustrated embodiment of my invention is approximately 120°. The position of the first hammer at the end of its driving stroke and of the driving means therefore (the crank 64 and block 70) at such time is shown by the full lines in Fig. 14.

When the gear 48 rotates further the cogwheel 52 will be disengaged thereby allowing the cogwheel 52, block 70, crank 64, and first hammer 78 to be returned to their starting positions by a spring 84 tensioned between a fixed point on the machine 18 and an arm 86 secured to the drive shaft 54.

It will be appreciated that when the hammer 78 starts to drive the nail it applies a force having a large component pointed opposite to the direction in which the tip of the nail is facing. This component tends to distort the nail shank and lift the nail away from the base of the machine. In order to prevent the applied force from thus interfering with driving of a nail, I have provided means for supporting and guiding a nail being driven whereby the force applied normal to the head of the nail is transmitted along the curved nail shank to the point thereof without distorting the nail or moving the same in any but the desired manner and direction. Said means comprises an arcuate groove 88 in the wall of the slot 80 facing the nail magazine. Said groove is coaxial with the driving slot and is of such depth and contour that it will snugly receive a lateral portion of a nail shank exposed by a nail head. The extent of such portion is determined by the amount the nail head is narrower than the nail shank, as clearly shown in Fig. 4. The angular position and configuration of the nail head 16 and groove 88 may be considerably varied provided only that the head is not allowed to prevent the flanks of adjacent nail shanks from remaining in contact while a nail is being driven. If desired or necessary, the variation may even be such as to provide a confining and guiding surface directly over a nail being driven. It will be understood, of course, that in such case the hammer element 78 must be inclined.

The foremost nail being driven is pressed into the groove 88 by spring means, hereinafter described, which form part of the nail magazine M.

It will be appreciated that the lifting reaction caused during initial driving of the curved nail is absorbed by the upper part of said groove and that a nail being driven is thus prevented from buckling, and is directed to the proper point of entry into material.

It will also be noted that although the nail turns during driving about a center at or very close to the surface of the material into which it is being driven, due to the necessity for providing the cogwheels 52, 58, the drive shaft 54 and, therefore, the crank 64 turn about a center spaced substantially above the turning center of the nail. Owing to the presence of this space

between the two centers and to the fact that the hammer 78 which is driven about one center must rotate at a uniform radius about the other, the distance between said hammer and the center of the drive shaft 54 will constantly vary during the driving of a nail. Such motion is obtained by allowing the roller 66 to freely slide in the slot in the crank 64. The hammer 78 is forced to travel in the desired path behind the head of a nail because the shoe 77 rides in the channel 72 which is parallel to said path.

It is impractical to drive a nail home in one blow by moving the first hammer a full 180° from its starting position (shown in Fig. 10) due to the fact that the block 70 and crank 64 would strike the material into which a nail is being driven before the hammer 78 could itself reach the material. Therefore, when a nail being driven covers an arc of substantially or close to 180°, the driving impulse applied by the first hammer will only suffice to drive the nail part way home and another impulse should be furnished by a second hammer to finish driving the nail. It will be realized that if the arc traversed by the first hammer is equal to or greater than the angular length of the curved nail being driven then no second hammer need be employed. However, since it may be desirable to use a curved self-retroverting nail covering an arc which is close to 180°, I have shown in conjunction with my nail driving machine 18 a second hammer and means for actuating the same.

The means for driving the second hammer derives power from the sleeve 60 which is turned by the mutilated cog-wheel 58. Said sleeve carries an integral disc 90 (Figs. 7 and 12) disposed intermediate the cogwheel 58 and crank 64. This disc supports a square post 92 which extends radially outward and is capped by a head 93. A bridge 94 is mounted on said post. The bridge includes a block portion 96 (Fig. 12) having a medially constricted aperture 98 through which the post 92 passes. The aperture is of such configuration as to permit the block to rock on the post about an axis parallel to the axis of the sleeve 60 and to slide longitudinally of the post. A spring 100 encircling the post 92 and held in compression between the head 93 and the block 96 biases the bridge 94 toward the center about which the disc 90 turns.

The bridge also includes a roller 102 coplanar with the crank 64 and adapted to ride on the periphery thereof. Another element carried by the bridge is a finger 104 hereinafter referred to as the "second hammer," which is coplanar with the first hammer and is urged by the spring 100 toward the driving slot 80. Finally, the bridge 94 includes a lug 106 to which a spring 108 is attached. The other end of said spring is fixed to a stationary point on the casing 22 whereby the bridge 94 and second hammer are biased to their starting positions (shown in Fig. 12). Intermediate the second hammer 104 and roller 102 the bridge has a hardened arcuate shoe 110 (Fig. 15) which is adapted to cooperate with a rail 112 comprising the top surface of one of the walls of the slot 80 when the second hammer is in driving position. This rail is a circular segment whose center is coaxial with the turning center of a nail.

It will be appreciated that when both hammers are in starting position (Fig. 12) and a nail 10 is in the slot 80 and lodged against groove 88 in the standard 62 ready to be driven, the second hammer 104, due to the presence of the nail

5 10 15 20 25 30 35 40 45 50 55 60 65 70

shank in the driving slot, is above said slot with its bottom resting on the nail shank. Shortly after the crank 64 starts to turn during initial driving of a nail, the periphery 114 thereof will contact the roller 102. This periphery functions as a cam surface and is so shaped that at the time the two hammer elements 78, 104 are radially aligned, the bridge 94 will be raised by the crank 64 to its uppermost position, shown by the dot and dash lines in Fig. 14, thus moving the second hammer out of the path of travel of the first hammer. After the first hammer has completed its working stroke (Fig. 14) and is being retracted by the spring 84, the crank periphery 114 will again raise the bridge 94 permitting said first hammer to repass beneath the second hammer. When the crank 64 and first hammer 78 are fully retracted, this position being defined by abutment of the block 70 and machine base 20, the cam-shaped periphery 114 facing the roller 102 is so close to the drive shaft 54 (Fig. 10) as to permit the bridge 94 to descend to a level such that the shoe 110 will rest upon the rail 112. In this position the second hammer will be disposed in the driving slot 80 with its forward face behind the head of a partially driven nail.

The mutilated portion of the gear 50 is so arranged that after the first hammer element has completed its driving stroke and the spring 84 has been given sufficient time to fully retract the first hammer, the operative portion of said gear 50 will mesh with the cogwheel 58 starting to drive the second hammer. This cogwheel will be driven by the unmutilated portion of the gear 50 the remaining angular distance necessary to drive the nail home, the position of the second hammer being shown in Fig. 16 at the end of its working stroke.

It will be noted that due to the configuration of the passageway 98 in the block 96, the bridge 94 can rock and slide during the working stroke of the second hammer, this being necessary since the second hammer, like the first hammer, travels during driving at a uniform radius about a center spaced from the center about which it is driven. Said second hammer is guided in its proper path of travel by the spring 100 which presses the shoe 110 against the rail 112.

The under-surface of the second hammer 104 is cut away, as at 115, to such an extent that when the second hammer is at the end of its working stroke there will be sufficient clearance behind it to enable the next nail to be driven to enter into the driving slot 80 in a manner shortly to be described. The second hammer is returned to starting position, which is defined by abutment of the post 92 and a wall of the casing 22, subsequent to completion of its working stroke by the spring 108, which will become effective after the mutilated gear 50 disengages the cogwheel 58.

It will be understood that a nail is supported and guided during operation of the second hammer by the same groove 88 which supported and guided it during operation of the first hammer.

60 65 70 75 80 85 90 95

As soon as the gear 50 disengages the cogwheel 58 the shaft 46 will have completed one revolution and the operative cycle of the machine will come to an end, the hammers and actuating means therefor having been restored to their starting positions by the springs 84, 108 there to await initiation of a new cycle when the button 42 is again depressed.

The nail magazine M comprises an arcuate shell 116 which extends forward from the standard 62 and on whose surface a supply of curved

nails lie. The portion of the shell adjacent the heads of the nails is provided with a channel 118 which extends into the driving slot 80 so that nails may freely move from the magazine into driving position. The magazine is covered by a cap 120 which frictionally engages the base 20 and machine housing 22. The shell 116 is provided with a longitudinal slot 122 through which the leg 124 of a pusher plate 126 freely projects. A spring 128 tensioned between this leg and a stationary point adjacent the standard 62 urges the pusher plate against the rearmost nail in the magazine and at the same time strongly presses the foremost nail being driven against the groove 88 in a side wall of the driving slot 80. For convenience, the several nails in the magazine prior to insertion may be loosely tacked together as with a light coat of varnish, lacquer, or the like.

The housing and cap may be provided with markers like the arrows 130 to assist in locating the point at which a nail will be driven by the machine.

The machine just described operates in the following manner upon depression of the button 42 to drive a curved nail. At the start of an operative driving cycle the foremost nail lies in the driving slot 80 with a flank portion thereof firmly pressed in the groove 88 by the spring 128 and pusher plate 126. At such time the head of the foremost nail is angularly disposed as indicated in Fig. 10 and is backed up by the face of the first hammer 78 which lies in the driving slot 80, the point of the nail being located adjacent the exit hole 82. When the one-revolution clutch is engaged upon depression of the button 42 the mutilated gear 48 will turn the cogwheel 52 causing the crank 64 to revolve and force the hammer 78 along the path it is desired to have the nail head travel. While the crank is turning its periphery 114 raises the bridge 94 and second hammer 104 out of the path of travel of the first hammer 78 as indicated by the dot and dash lines in Fig. 14. After the stroke of the first hammer is completed and the mutilated gear 48 and cogwheel 52 disengaged, the first hammer will be retracted by the spring 84. During retraction neither cogwheel 52, 58 is turned although the shaft 46 continues to rotate. Retraction of the first hammer and its associated crank 64 will permit the bridge 94 to drop into operative position with the shoe 110 against the rail 114 and with the second hammer 104 in the slot 80. Immediately this has occurred, the operative portion of the mutilated gear 50 will engage the cogwheel 58 causing the same to drive the second hammer to the position in Fig. 16. In this position the nail will be driven completely home with its head slightly below the surface of the material into which it is entering.

It will be appreciated that while a nail is being driven or as long as even a portion thereof or of either of the hammers 78, 104 remain in the slot 80, the next succeeding nail cannot be forced into said slot by the spring 128. This is particularly true since all the nails must remain in parallel relationship due to the fact that they are lightly tacked together and are closely confined in the space between the shell 116 and cap 120. However, after the foremost nail being driven has had its head embedded into the material and the first hammer is in the position shown in Fig. 10 and the second hammer in the position shown in Fig. 16, the driving slot will be clear so that the next succeeding nail can enter therein. The second hammer, upon retraction, 75

will be cammed radially outwardly by the tip of said next succeeding nail and will ride back to its starting position while resting upon the top of the shank of the nail in said slot.

5 It may be mentioned that the energy for driving the two hammers is supplied by the flywheel 28 which necessarily slows down somewhat during the driving cycle, the relative change in the angular speeds of said flywheel and of the motor shaft 26 being permitted by the slip drive 30.

10 It will thus be seen that there is provided a device and method for using the same in which the several objects of this invention are achieved, and which is well adapted to meet the conditions of practical use.

15 As various possible embodiments might be made of the above invention, and as various changes might be made in the embodiment above set forth, it is to be understood that all matter herein set forth or shown in the accompanying drawings is to be interpreted as illustrative and not in a limiting sense.

20 Having thus described my invention, I claim as new and desire to secure by Letters Patent:

25 1. A driving tool for elongated nails having longitudinally curved shanks which extend over at least 90°, said tool comprising means for supporting a curved nail and means for applying to the head of the nail a driving force which changes its direction as the nail is driven in such manner that said force is always directed substantially perpendicular to the nail head.

30 2. A driving tool for elongated nails having longitudinally curved shanks, said tool comprising means for supporting a curved nail, means for applying to the head of the nail a driving force which changes its direction as the nail is driven in such manner that said force is always directed substantially perpendicular to the nail head, and means for guiding the nail shank for arcuate movement as it is driven.

35 3. A driving tool for elongated nails having longitudinally curved shanks, said tool comprising means for supporting a curved nail, means for applying to the head of the nail a driving force which changes its direction as the nail is driven in such manner that said force is always directed substantially perpendicular to the nail head, self-contained power means for actuating said force applying means, and means for guiding the nail shank for arcuate movement as it is driven.

40 4. A driving tool for elongated nails having longitudinally curved shanks, said tool comprising means for supporting a curved nail, means for applying to the head of the nail a driving force which changes its direction as the nail is driven in such manner that said force is always directed substantially perpendicular to the nail head, a motor for actuating said force applying means, and means for guiding the nail shank for arcuate movement as it is driven.

45 5. A driving tool for elongated nails having longitudinally curved shanks, said tool comprising means for supporting a curved nail, means for applying to the head of the nail a driving force which changes its direction as the nail is driven in such manner that said force is always directed substantially perpendicular to the nail head, self-contained power means for actuating said force applying means, a clutch intermediate said power means and said force applying means, manually controlled means for operating said clutch, and means for guiding the nail shank for arcuate movement as it is driven.

11

6. A driving tool for elongated nails having longitudinally curved shanks, said tool comprising means for supporting a curved nail, means for applying to the head of the nail a driving force which changes its direction as the nail is driven in such manner that said force is always directed substantially perpendicular to the nail head, self-contained power means for actuating said force applying means, a one-revolution clutch intermediate said power means and said force applying means, manually controlled means for engaging said clutch, and means for guiding the nail shank for arcuate movement as it is driven.

7. A driving tool for elongated nails having longitudinally curved shanks, said tool comprising means for supporting a curved nail, means for feeding one nail at a time to said supporting means, and means for applying to the head of the nail a driving force which changes its direction as the nail is driven in such manner that said force is always directed substantially perpendicular to the nail head.

8. A driving tool for elongated nails having longitudinally curved shanks, said tool comprising means for supporting a curved nail, a magazine means for feeding one nail at a time from said magazine to said supporting means, and means for applying to the head of the nail a driving force which changes its direction as the nail is driven in such manner that said force is always directed substantially perpendicular to the nail head.

9. A driving tool for elongated nails having longitudinally curved shanks, said tool comprising a plurality of members which define a curved passageway for supporting and guiding said nail for arcuate movement during driving thereof, and driving means for applying a force to the head of the nail being driven through said passageway in such manner that said force is always directed substantially perpendicular to the nail head.

10. A tool as set forth in claim 9 wherein said driving means comprises a hammer element which moves along a curved path behind the head of a nail being driven.

11. A tool as set forth in claim 9 wherein said driving means comprises a pair of hammer elements, each of which move along successive portions of a curved path behind the head of a nail being driven.

12. A tool as set forth in claim 9 wherein said driving means comprises a pair of hammer elements, each of which move along successive portions of a curved path behind the head of a nail being driven, and means to move the last acting of said elements out of the path of the first acting of said elements during actuation of said first acting element.

13. A tool as set forth in claim 9 wherein said driving means comprises a pair of hammer elements, each of which move along successive portions of a curved path behind the head of a nail being driven, means to move the last acting of said elements out of the path of the first acting of said elements during actuation of said first acting element, means to retract said first acting element after actuation thereof, and means to place said second acting element behind the head of the nail after said first acting element is retracted.

14. A tool for driving elongated nails having longitudinally curved shanks, said tool comprising means for supporting and guiding a curved nail

12

for arcuate movement during driving thereof, a shaft, means for rotating said shaft, a slip drive driven by said shaft, a fly-wheel driven by said slip drive, a hammer element driven by said fly-wheel for applying a force to the head of a nail, said element being movable along a curved path.

15. A tool as set forth in claim 14 wherein a clutch is disposed intermediate said fly-wheel and said hammer element.

16. A tool as set forth in claim 14 wherein a one-revolution clutch is interposed between said fly-wheel and said hammer element and wherein said clutch is controlled by manually operable trip means.

17. A driving tool for driving elongated nails having longitudinally curved shanks about a center substantially coincident with the surface of the material into which the nail is being driven, said tool comprising a hammer element, means to guide said element at a uniform radius about a center coincident with said nail turning center, and means to drive said nail about a center spaced from said turning center.

18. A driving tool for driving elongated nails having longitudinally curved shanks about a center substantially coincident with the surface of the material into which the nail is being driven, said tool comprising a hammer element, means to guide said element at a uniform radius about a center coincident with said nail turning center, and means to drive said nail about a center spaced from said turning center, said guide means and said drive means being connected by means which permits relative rocking and sliding movement thereof.

19. A driving tool for elongated nails having longitudinally curved shanks, said tool comprising means for supporting and guiding a curved nail for arcuate movement during driving thereof, a hammer, means to direct said hammer through an arcuate path of travel substantially coincident with the path of travel of the nail head, and means to move said hammer through said path in the direction the nail is to be driven, whereby to apply a driving force to the head of the nail throughout the time it is driven, which force changes its direction as the nail is driven in such manner as to always be directed substantially perpendicular to the nail head.

20. A driving tool for elongated nails having longitudinally curved shanks, said tool comprising means for supporting and guiding a curved nail for arcuate movement during driving thereof, a hammer, means to direct said hammer through an arcuate path of travel substantially coincident with the path of travel of the nail head, means to move said hammer through said path in the direction the nail is to be driven whereby to apply a driving force to the head of the nail throughout the time it is driven, which force changes its direction as the nail is driven in such manner as to always be directed substantially perpendicular to the nail head, a magazine to house a supply of curved nails, and means to feed one nail at a time to said supporting and guiding means.

21. A tool as set forth in claim 19 wherein the hammer is moved through an arc shorter than the arcuate length of the nail, and wherein a second hammer directed and moved in a manner similar to the first hammer is provided to drive the nail for the remainder of its angular length.

22. A driving tool for elongated nails having longitudinally curved shanks, said tool comprising

75

ing means for supporting and guiding a curved nail for arcuate movement during driving thereof, a pair of hammers, means to direct one of said hammers through an arcuate path of travel substantially coincident with an initial portion of the path of travel of the nail head, means to direct the other hammer through an arcuate path of travel substantially coincident with the remainder of the path of travel of the nail head, separate means to move first one and then the other of the hammers through their paths whereby to apply a driving force to the head of the nail throughout the time it is driven, which force changes its direction as the nail is driven in such manner as to always be directed substantially perpendicular to the nail head, said second hammer being located in the path of travel as the first hammer, and means to move said second hammer towards and away from such position whereby said first hammer may drive the nail head beyond the second hammer before the second hammer completes driving of the nail.

23. A tool as set forth in claim 22 wherein the means for moving the second hammer out of its position lying in the path of travel of the first hammer is associated with the first hammer.
- 5 24. A driving tool for elongated nails having longitudinally curved shanks, said tool comprising a bed, means carried by said bed for supporting and guiding a curved nail for arcuate movement during driving thereof, a hammer, 10 means supported by said bed to direct said hammer through an arcuate path of travel substantially coincident with the path of travel of the nail head, means to move said hammer through said path in the direction the nail is to be driven, 15 whereby to apply a driving force to the head of the nail throughout the time it is driven, which force changes its direction as the nail is driven in such manner as to always be directed substantially perpendicular to the nail head, and an 20 electric motor also carried by said bed for actuating said hammer moving means.

JOHN N. M. HOWELLS.
